UNITED STATES PATENT OFFICE.

ARTHUR HANTSCH, OF LINDEN, NEW JERSEY.

CARRYING MECHANISM.

1,074,086.

Specification of Letters Patent. Patented Sept. 23, 1913.

Application filed April 15, 1912. Serial No. 690,732.

To all whom it may concern:

Be it known that I, ARTHUR HANTSCH, a citizen of the German Empire, and a resident of Linden, Hudson county, New Jersey, have invented certain new and useful Improvements in Carrying Mechanisms, of which the following is a specification.

This invention relates to improvements in carrying mechanisms for calculating machines.

The object of the invention is to simplify the construction and design of certain parts or elements of the carrying mechanism and to provide means for a better and more positive operation than is possible with other constructions known to the art.

In the drawings illustrating my invention and accompanying this specification Figure 1 is a partial plan view of a calculating machine illustrating my invention, Fig. 2 is a side elevation of the parts shown in Fig. 1. Fig. 3 is a transverse sectional view. Figs. 4, 5, 6 and 7 are detail views of my improved counting drum particularly illustrating the movable tooth carried thereon. Fig. 8 illustrates a certain oscillating circular lever for operating the movable tooth. Fig. 9 illustrates in detail the movable tooth. Fig. 10 illustrates in detail the cover plate for the tooth. Fig. 11 shows the tooth operating slide. Fig. 12 shows the tooth operating lever and cam. Fig. 13 illustrates steps in the operation of my device. Fig. 14 is a detail view of the locking lever. Fig. 15 is an enlarged view of the counting drum and its associated parts including the movable tooth and Fig. 16 is a plan view showing how the movable tooth is supported and operated on a toothless counting drum.

Referring to Figs. 1, 2 and 3 the numeral 1 represents the framework in which the counting drums 2, 2 are journaled in known manner. Each drum is as usual provided with nine teeth. 3, 3, are the tens wheels slidably supported on the square shafts 4 which also carry the locking wheels 5 which coöperate with the locking cams 6 of the counting drums.

7, 7 are the usual number wheels each of which is provided with the carrying arm 8. 9 is the counting drum operating shaft which is rotated from the shaft 10 in the usual manner by a handle, not shown.

One object of my invention is to provide a more positive drive of the counting drums

from the shaft 9 than is possible by means of individual gearing. To this end I drive only the two end shafts 11, 11 by gears 12, 12 from the driving shaft 9, and on the inner end of each counting drum shaft 11 I mount a crank 13, and all of the latter are connected by a single connecting rod 14. By this means all the counting drums are operated positively at one and the same time and I dispense with a great many gears which otherwise would be needed for this purpose. The positive driving connection between the counting drums prevents all lost motion and is very advantageous and simple to build.

Another object of my invention is to eliminate the separate tens transferring tooth as an independent separate element mounted and operated away from the counting drums, which necessitates a complicated construction comprising numerous parts such for instance as shown in Patent Number 938,791 of November 2, 1909. I also provide an improved locking mechanism for the tens transferring means.

In this instance I mount the tens transferring tooth directly on the counting drums as a movable tooth thereon and provide a suitable operating mechanism therefor.

Referring to the Figs. 4 to 15 it will be seen that the counting drum 2 is cut out to form sockets 15, 15 in which are secured pins 16, 16, Fig. 5. On the latter are pivoted circular swinging levers 17, 17. Each lever has an aperture 18 to fit over its pin 16, Fig. 8, and carries two pins 19 and 20. The pins 20 enter apertures 21 in the movable tooth 22 Fig. 9, to operate said tooth, and the pins 19 enter apertures 23 in the slide 24— Fig. 11. The slide has stops 25 which enter into and coöperate with the cut out portions 26 in the tooth. The slide carries a pin 27. 28 is a cover plate which is fastened to the counting drum by a screw 29, Fig. 4, 100 and which also has an opening 30, Fig. 10.

31 is a lever with a notched end 32, Fig. 12, adapted to enter through the opening 30 in the cover plate and receive the pin 27 of the slide as shown in Fig. 7.

Figs. 5 and 6 show clearly the operation of the movable or tens transferring tooth. It will be seen that in Fig. 5 the tooth is in inactive position below the periphery of the counting drum. In Fig. 6 the slide 24 is at the extreme right, having been brought into this position by the lever 31 engaging

the pin 27. As the slide is moved to the right, the swinging levers 17 operate the tooth to the right and radially outward to project the tooth beyond the periphery of the counting drum and into active position. 5 The tooth is provided with a slot 33 which fits over the screw 29 aforesaid. The lever 31 is guided on the drum in a cut out portion as at 60 in the locking cam 6.

10 The stops 25 and cut out portions 26 cooperate to guide the movement of the tooth. Each counting drum except the first one—the one to the right in Fig. 1—is provided with a tens transferring tooth. The shafts 15 11 to the left are provided with very short toothless drums 34 and a correspondingly short tooth 35 operated by means of a single swinging lever 67 pivoted on the drum 34 in a socket 65 in the same manner in which the levers 17 are pivoted on the drums 2. 20 The lever 61 extending from the collars 68 actuates the lever 65 which, by being oscillated, projects the tooth 35 radially outward from the drum. The tooth is carried in a 25 socket in the drum and it and the lever 67 are prevented from displacement by a cover plate 78 similar to cover plates 28 aforesaid.

30 79 is an abutment on drum 34 against which the tooth 35 slides. When the short tooth 35 is moved into active position it engages at the proper time the gear 36 to operate the last number wheel in a known manner.

35 The lever 31 is provided with a hub 37 and a collar 38 having a cam 39. The lever 31 is reciprocated on the counting drum by the following means.

40 On the frame is suitably pivoted at 40 a carrying lever 41 which has a lug 42 which engages the collar 38 and which also carries a roller 43 adapted to coöperate with an oscillating arm 44, pivoted at 45. When, during the operation of the machine, the tens wheel has been engaged by the counting 45 drum and the corresponding number wheel registers naught, the carrying arm 8 strikes the arm 44 which throws the roller 43 inward and oscillates the carrying lever 41. Consequently the collar 38 or 68 in Fig. 50 16 is moved to the right in Fig. 7 and the tens transferring tooth is projected into active position to engage the next or adjacent tens wheel, which in turn operates the next number wheel and so on as is known.

55 In order to prevent an incomplete operation I provide means for positively holding the lever 31 in its retracted position when the same has been operated by the carrying lever 41.

60 Referring to Figs. 3, 13 and 14 the numeral 47 represents a locking hook pivoted at 48 and suitably secured to the frame. A spring 49, only shown in Fig. 14, tends to keep the hook horizontally. The collar 38 65 is cut out as at 50. Normally the hook and

collar are in the position shown at the top in Fig. 13, that is, the hook is in engagement with the collar but the cut out portion 50 is opposite the hook. Consequently, the collar is free to move axially on the 70 counting drum shaft 11 when actuated by the carrying lever 41. The axial and at the same time rotary movement of the collar 38 forces the hook aside as shown in the second position in Fig. 13 and immediately 75 thereafter the collar completes its axial movement and the hook snaps over said collar and locks it as shown at the bottom of Fig. 3, that is during the tens transferring movement, thus absolutely locking the 80 collar against accidental return movement, an occurrence which is apt to happen with a less positive locking device. When, however, the arm 44 moves back into normal position, the cam 39 again moves the collar 85 38 to the left in Fig. 3, which it can do by that time the cut out portion 50 is again opposite the hook and the collar can pass the latter. The hook now again engages the 90 collar to lock the same.

95 It will be seen that first, I have provided a positive drive for the counting drums. Second, the tens transferring tooth is placed directly on said drum, a feature which I believe to be broadly new, and a very simple carrying mechanism is provided in the space between two counting drums. Finally a positive locking device is provided to insure the active position of the tens transferring tooth.

100 I do not wish to be restricted to the exact details shown or described except as the appended claims demand.

I claim:

1. In a mechanism for advancing the tens 105 wheel in calculating machines, a counting drum, a tens transferring tooth carried by the said drum, means carried by the latter for operating said tooth and a lever in operative engagement with said counting 110 drum, for actuating the said operating means.

2. In a mechanism for advancing the tens 115 wheel in calculating machines, the combination of a counting drum, a tens transferring tooth, means supported on said drum for operating said tooth and a locking device for preventing incomplete action of the said means.

3. In a mechanism for advancing the tens 120 wheel in calculating machines, the combination of a counting drum, a tens transferring tooth mounted on said drum, a member supported on the latter for operating said tooth, means for operating the said member and a 125 locking device for preventing incomplete action of the said member.

4. In a mechanism for advancing the tens 130 wheel in calculating machines, the combination of a counting drum, a tens transferring

- tooth mounted on said drum, a reciprocating member for operating said tooth, means for reciprocating said member and a locking device for locking said reciprocating member against incomplete action thereof. 5
5. In a mechanism for advancing the tens wheel in calculating machines, the combination of a counting drum, a tens transferring tooth, operating connections between the latter and the said drum, a movable member for operating said tooth, means for actuating said member and a locking device for preventing incomplete action of the latter. 10
15. 6. In a mechanism for advancing the tens wheel in calculating machines, the combination of a counting drum, a tens transferring tooth supported in said drum, operating connections between the latter and the said tooth, a reciprocating member adapted to move on a portion of said drum, means for actuating said member to operate the said tooth and a locking device for preventing incomplete action of said member. 20
25. 7. In a mechanism for advancing the tens wheel in calculating machines, the combination of a tens wheel, a counting drum, a tooth movably carried by the latter, means for operating said tooth to engage said tens wheel and a locking device for preventing incomplete action of the said tooth. 30
35. 8. In a mechanism for advancing the tens wheel in calculating machines, the combination of a tens wheel, a counting drum, a tooth movably carried by the latter, means carried by the said drum for operating said tooth to engage said tens wheel and a locking device for preventing incomplete action of the said tooth. 40
45. 9. In a mechanism for advancing the tens wheel in calculating machines, the combination of a tens wheel, a counting drum, a tooth movably carried by said drum and adapted to engage said tens wheel, a member for operating said tooth, a collar secured to said member and a hook adapted to engage said collar to prevent incomplete action by the said member. 50
55. 10. In a mechanism for advancing the tens wheel in calculating machines, the combination of a tens wheel, a shaft, a tooth adapted to engage said tens wheel, means for supporting said tooth on the said shaft, a member slidably supported on the latter for actuating the said tooth and means for operating the said member. 60
65. 11. In a mechanism for advancing the tens wheel in calculating machines the combination of a tens wheel, a shaft, a tooth adapted to engage said tens wheel, means for supporting said tooth on the said shaft, a member slidably supported on the latter for actuating the said tooth, and a locking device for preventing incomplete action of the said member. 65
12. In a mechanism for advancing the tens wheel in calculating machines, the combination of a tens wheel, a counting drum, a movable tooth on the latter for actuating said tens wheel, a member in operative engagement with the said tooth, means for imparting a sliding motion to said member and mechanism for preventing return sliding motion of said member before said tooth has actuated said tens wheel. 70
13. In a mechanism for advancing the tens wheel in calculating machines, the combination of a tens wheel, a counting drum, a tens wheel actuating tooth supported on said drum and adapted to be projected beyond the periphery of said drum to engage said tens wheel, a member for operating said tooth, a collar secured to said member, a pivoted hook in engagement with said collar to lock the same to prevent incomplete action of the said member and means for operating the latter. 75
14. In a mechanism for advancing the tens wheel in calculating machines, the combination of a tens wheel, a counting drum, a movable member on said drum adapted to engage the said tens wheel, a member for operating said tooth, a collar having a low portion and an annular groove secured to said member, a rocking lever extending with one end into said annular groove and adapted to reciprocate the said member, a pivoted hook in engagement with said annular groove and adapted to be moved out of said annular groove by the said low portion of the said collar when the said rocking lever is operated and a spring for automatically causing said hook to engage the said collar outside of said annular groove to prevent incomplete action by said tooth operating member. 80
15. In a mechanism for advancing the tens wheel in calculating machines the combination of a plurality of counting drums, a number wheel for each of said drums for registering the operation thereof, a tens wheel for each drum for operating said number wheels, a movable tooth supported on each of said drums and means for operating said movable tooth to cause the same to rotate the said tens wheel. 85
16. In a mechanism for advancing the tens wheel in calculating machines the combination of a plurality of counting drums, a number wheel for each drum for registering the operation thereof, a tens wheel for each drum for operating said number wheel, a movable member on each of said drums and means for automatically operating said movable member to cause the same to actuate the said tens wheel. 90
17. In a mechanism for advancing the tens wheel in calculating machines the combination of a plurality of counting drums, a number wheel for each of said drums for 100
- 110
- 115
- 120
- 125
- 130

registering the operation thereof, a tens wheel for each of said drums for operating the corresponding number wheels, a movable tooth carried by each of the said drums, 5 means for automatically operating said movable tooth to cause the same to actuate the tens wheel and a device for preventing incomplete action of the said means.

18. In a mechanism for advancing the tens wheel in calculating machines the combination of a counting drum, a number wheel for registering the operation thereof, a tens wheel, a movable tooth on said drum and operating connections between the said 15 number wheel and the said movable tooth for operating the latter to actuate the said tens wheel.

19. In a mechanism for advancing the tens wheel in calculating machines the combination of a counting drum, a number wheel for registering the operation thereof, a tens wheel, a movable member supported on said drum and means interposed between the said number wheel and the said 25 movable member for automatically operating the latter to actuate the said tens wheel.

20. In a mechanism for advancing the

tens wheel in calculating machines the combination of a counting drum, a number wheel for registering the operation thereof, 30 a tens wheel, a movable tooth carried by the said drum, operating connections between the said number wheel and the said movable tooth for operating the latter to actuate said tens wheel and a locking device for preventing incomplete action of said operating 35 connections.

21. In a mechanism for advancing the tens wheel in calculating machines the combination of a tens wheel, a counting drum, a 40 tooth movably carried by the latter and adapted to engage said tens wheel, a number wheel for registering the operation of the said counting drum, a member for operating said movable tooth and means for 45 actuating said member by the said number wheel.

Signed at New York, N. Y. this 13 day of April 1912.

ARTHUR HANTSCH.
